UNITED STATES PATENT OFFICE.

EDWARD NALL, OF AKRON, OHIO; EDITH ALICE NALL, OF CUYAHOGA FALLS, OHIO,
EXECUTRIX OF SAID EDWARD NALL, DECEASED, ASSIGNOR TO THE GOODYEAR
TIRE AND RUBBER COMPANY, OF AKRON, OHIO, A CORPORATION OF OHIO.

MULTIPLE VULCANIZING-PRESS.

1,316,105.

Specification of Letters Patent. Patented Sept. 16, 1919.

Application filed September 23, 1916, Serial No. 121,784. Renewed July 17, 1917. Serial No. 181,166.

To all whom it may concern:

Be it known that I, EDWARD NALL, a citizen of the United States, residing at Akron, in the county of Summit and State of Ohio, 5 have invented new and useful Improvements in Multiple Vulcanizing-Presses, of which the following is a specification.

My present invention relates to the class of vulcanizing presses and more particularly relates to a multiple press organized from a battery of individual press elements which are capable of successive operation by a single workman, who is thus enabled to employ the time required to cure the article placed in any one press by loading or unloading the remaining presses of the battery in turn.

As a principal object I contemplate the provision of a multiple vulcanizing press 20 organized from a battery of separate press elements which are capable of operation in pairs, although the separate operating elements of each pair of presses may be capable of a differential movement with respect 25 to each other, in accordance with the requirement of the separate articles to be vulcanized in each.

It is also an object of this invention to construct a multiple vulcanizing press in 30 such a manner that a battery of separate press elements are capable of independent operation against a single fixed head, which does duty for the entire battery.

It is an object of equal importance to arrange 35 the various elements of the battery composing my multiple press in such a manner that they may be commonly fed from a single source of actuating fluid, and may be commonly guided, in their travel against the 40 fixed head and return, by a single guide element.

The above and additional objects of a similar nature, which will be hereinafter more specifically treated, may be accomplished by such means as are illustrated in 45 the accompanying drawing, described in the following specification and then more particularly pointed out in the claims which are appended hereto and form a part of this 50 application.

With reference to the drawings, wherein there has been illustrated a preferred embodiment of the invention as it is reduced to

practice, and throughout the several views of which, similar reference numbers designate corresponding parts:

Figure 1 is a front elevational view of the compound vulcanizer comprehended by this invention;

Fig. 2 is an end view of the multiple vulcanizer; and

Fig. 3 is a transverse sectional view taken through my vulcanizing apparatus on the planes indicated by the broken lines 3—3 of Fig. 1.

In the vulcanization of articles requiring but short curing periods much time is lost by the operator remaining idle while the article in the vulcanizer is being cured, prior to the removal of the cured article from the 70 vulcanizer and the substitution of the next article to be cured therein.

Particularly, this is the case in connection with the manufacture of inner tubes of the smaller sizes, which are adapted to be used 75 within bicycle and motorcycle tire casings. It is the practice to roll these tubes from a continuous strip of raw stock, and then to cut the ensuing continuous raw tube to the proper lengths. The extremities of these 80 tubes are then to be subjected to a butt end vulcanization, *i. e.*, one in which each end of the tube is closed tightly independently of the other end, such butt vulcanization taking place, of course, only after the tube has 85 been cured as a whole.

According to my invention it is possible to simultaneously vulcanize both ends of a tube, a plan having economic advantages 90 over any method which proposes the vulcanization of the tube ends at intervals. For this reason I arrange the press elements of my vulcanizing battery in pairs in order that each element of a pair may serve to cure one end of the same tube. Since, however, the 95 thickness of the material in the tube itself frequently varies, I have arranged the pairs of presses so that the separate elements are individually, although simultaneously, operable. By providing a multiple press 100 which contains a battery of paired press elements, the laborer is permitted to spend the time required for the vulcanization of tube ends, operated upon by any pair of the elements, in loading or unloading the remaining pairs of presses, in their turn.

A single machine base suffices for the support of the entire battery of press vulcanizers. This machine base includes spaced standards 5 which are cross-connected by channel beams 6, the latter being secured by suitable means 7 in spaced relation to each other and serving to support a base plate 8. Upon this base plate is mounted a plurality of pressure chambers 9 which are fed with an operating fluid through the medium of pipes 10 arranged between the spaced beams 6, as is clearly shown in Fig. 3. The pressure chambers 9 are paired for simultaneous operation by means of elbow joints 11 which connect pairs of adjacent pipes 10. From each compound joint 11 there extends a supply pipe 12 through which the fluid of pressure is to be transmitted to be paired pressure chambers 9 upon proper operation of the valve 13, which is located within the supply pipe 12 and at the intersection therewith of feed pipes 14 and 15. The feed pipe 14 serves to connect the supply pipe 12, through its valve, with the inlet manifold 16 through which steam or a similar actuating fluid is fed to the entire battery of press elements from a suitable source. The feed pipe 15 connects the supply pipe 12, through its valve, with the exhaust manifold 17, which also serves for all of the separate presses of the vulcanizing battery.

The valves 13 are of the two-way type and so constructed that each is capable of affording communication between either of the feed pipes 14 and 15 and the main supply pipe of its respective pair of presses while shutting off the other feed pipe from the supply pipe. This type of valve is too well known to the art to require any specific illustration. A lever arm 18 is secured upon the protruding extremity of each valve stem and is connected by a vertical link 19 with the extremity of an operating lever 20, one of these levers being arranged for each pair of press elements. The levers 20 are intermediately pivoted upon the ears 22 which depend from the channel bar 23. The latter is supported upon the standards 24 which are erected upon the base frames 5 and which also serve to support the fixed head 25 of the machine.

The bar 23 is apertured at intervals along its length to serve as a guide for the pistons 26, the latter being operable within respective pressure chambers 9. Caps 27, provided with some suitable leak-preventing packing form closures for the upper ends of the pressure chambers.

A movable press head 28 is carried upon the extremity of each of the pistons 26, these press heads being formed hollow in order that steam may be conducted through a suitable duct within the supporting piston for the purpose of heating the press head. The fixed press head 25 is also formed hollow and

is adapted to be filled with live steam from a suitable feed pipe 29. A longitudinal partition 30 is erected interiorly of the hollow fixed head 25 and longitudinally thereof as a strengthening element, this partition being provided with apertures 31 at intervals along its length in order that free communication for the heating fluid may be established between the two compartments provided by this partition. The temperatures within the fixed head may be gaged by means of the thermometer 32.

Each of the movable press heads 28 carries a shelf 33 secured by bracket means 34 to one side thereof, and upon this shelf may rest the end portions of the tube to be vulcanized. In Fig. 1 there is illustrated the vulcanization of both ends 35 and 36 of a single tube, and it will be apparent that each end is given a similar, but separate, vulcanization at the same time, so that any differences in the thickness of material in the different ends may be compensated for by different throws or travels, on the part of the pair of press pistons. After loading the first pair of press elements, and moving the operating lever 20 to permit an ingress of the actuating fluid into the pressure chambers 9 of this pair of elements, the operator may proceed to similarly load the remaining pairs of presses in succession, returning after the loading of the last pair of presses to the first press for the removal of the tube whose butt ends have been vulcanized.

What I claim is:

1. A multiple vulcanizing press having a plurality of press units, means for operating the press units in pairs, and means to control the operation of any pair of the press units at will.

2. In a multiple vulcanizing press, a battery of movable press elements arranged in pairs and a single fixed press head serving for all of said pairs.

3. In a multiple vulcanizing press, a battery of movable press elements arranged in pairs; means for moving press elements of each pair simultaneously, said means permitting varying relative movement of the press elements of each pair.

4. In a multiple vulcanizing press, a single fixed head; an inlet manifold; an outlet manifold; and separate press elements independently operable in pairs against said fixed head and connected in pairs to said manifolds.

5. In a multiple vulcanizing apparatus, a single fixed head; a single guide; intake and exhaust manifolds; and separate press elements independently operable in pairs against said fixed head and commonly controllable by said guide, the pairs of said elements being connected to said manifolds.

6. In a vulcanizing press, a plurality of separate press elements associated in pairs,

and means for operating at will any pair of the press elements simultaneously.

7. In a vulcanizing press, a battery of separate press elements arranged for independent vertical movement, means to operate the press elements in pairs at will; and a fixed press head serving for all of said separate press elements.

8. In a vulcanizing press, a plurality of independently movable press elements associated in pairs, and fluid-actuated means for effecting at will simultaneous movement of any pair of the elements.

9. In a multiple vulcanizing press, a plurality of separate press elements, said elements being associated in pairs in such a manner that the time required for loading and unloading certain of the press elements may be utilized for vulcanization of articles operated on by others of said elements, and

means for operating any pair of the elements at will.

10. A vulcanizing press having a pair of independent press elements, and means whereby the pair of press elements are simultaneously operable and capable of a differential movement with respect to each other in such a manner that both ends of an article to be cured, such as an inner tube, may be vulcanizing simultaneously, yet with such variations as may be necessitated by the differing requirements of the respective ends of the article.

In testimony whereof I have signed my name in the presence of two subscribing witnesses.

EDWARD NALL.
